COMBINED ESCUTCHEON AND HANDLE FOR DOORS

Owen R. Crain, San Gabriel, Calif., assignor to
Victor M. Carter, Los Angeles, Calif.

Application July 31, 1950, Serial No. 11,503

Term of patent 14 years

(Cl. D10—8)

To all whom it may concern:

Be it known that I, Owen R. Crain, a citizen of the United States, residing at San Gabriel, in the county of Los Angeles, State of California, have invented a new, original, and ornamental Design for a Combined Escutcheon and Handle for Doors, of which the following is a specification, reference being had to the accompanying drawing, forming part thereof, in which:

Fig. 1 is a front elevational view of a combined escutcheon and handle for doors, showing my new design;

Fig. 2 is a side elevational view;

Fig. 3 is a top view;

Fig. 4 is a bottom view; and

Figs. 5 and 6 are sectional views thereof taken on the lines 5—5 and 6—6 respectively of Fig. 2.

I claim:

The ornamental design for a combined escutcheon and handle for doors, substantially as shown.

OWEN R. CRAIN.
